UNITED STATES PATENT OFFICE.

VALENTINE BORST, OF NEW YORK, N. Y.

IMPROVEMENT IN HARNESS-SADDLES.

Specification forming part of Letters Patent No. 125,011, dated March 26, 1872.

To all whom it may concern:

Be it known that I, VALENTINE BORST, of the city, county, and State of New York, have invented a new and useful Improvement in Harness-Saddles; and I do hereby declare the following to be a full, clear, and exact description thereof, which will enable those skilled in the art to make and use the same, reference being had to the accompanying drawing forming a part of this specification, in which drawing—

Figure 1 is a vertical section lengthwise of the saddle in the line 1 1 of Fig. 2. Fig. 2 is a cross-section from front to rear of the saddle in the line x x of Fig. 1. Fig. 3 is a section in the line y y of Fig. 2. Fig. 4 is a cross-section in the line z z of Fig. 1. Fig. 5 is a cross-section in the line z' z' of Fig. 1. Fig. 6 is a top view of the center of the saddle, the metal frame and wooden mountings being left bare.

Similar letters indicate corresponding parts.

This invention relates to harness-saddles, and embodies several novel features, one of which consists in the manner in which the wooden mountings are fitted and secured to the frame, whereby I am enabled to fit them snugly and accurately to the frame. The summit or apex of the frame, at the bearings where the cantel and check-hook are attached, is raised above the adjacent parts of the frame, and the wooden mountings are cut away at the parts which correspond to the positions of the said bearings, leaving only a narrow continuous strip of wood where the mountings extend past the bearings, whereby I am enabled to bend the wooden mountings with facility to make them conform to the irregular shape of the metal frame on which they are to be fitted. One or both of said bearings are made to project over the rest of the frame, along a portion of their ends, so that the edges of the wooden mountings, at the place where they are cut off, can be sprung under the projecting edges of the bearings, so as to confine the separated edges of the wooden mountings to the metal frame. These elevated bearings can be plated so as to have an ornamental appearance, and the jockey can be omitted without offense to the eye. Another feature consists in an improved cantel, which, instead of extending across the saddle, as heretofore, stops at the place where it is secured to its bearings. The

half-cantel thus made has a metallic mounting, by which the cantel can be firmly fastened to the frame without injuring the wood of the cantel. The ends of the metal saddle-frame are made with an under shoulder, to receive a perforated sheet-metal extension, to which the flap is riveted, the sheet metal making a flush joint with the metal frame on the under side. The central part of the flap is connected to the sheet-metal extension, and produces a smooth flush surface on the upper side, because its upper edge comes against the square end of the metal frame. Another novel feature consists in removable bearings for fastening the terrets to the saddle. These bearings extend over the back-band channel, and have been heretofore made permanent parts of the saddle-frame. I have invented a mode of making them removable by forming grooves, or their equivalents, in the sides of such channel and sliding the bearings into their places, where they are secured by the leather mountings and the terrets when the parts are put together. The terrets are made with tapped shanks, so as to form nuts, by which the terrets and bearing-plates are secured to each other.

The letter A designates the metallic saddle-frame; and B B, the wooden mountings, which are cut away for a portion of their width to enable me to fit them to the edges of the elevated bearings C C of the frame. By elevating these bearings the cantel D and check-hook E are allowed to have a more convenient and better support than when the bearings are level with the rest of the frame; and, furthermore, by raising these bearings, which occur at the summit of the saddle, I am enabled to fit the wooden mountings more snugly, and with greater ease, to the frame, by cutting away so much of their width as is required to make room for the bearings, the wooden mountings and the raised bearings being left flush with each other. I also use the bearings to assist in holding the wooden mountings down to the frame by causing their edges to project over the adjacent parts of the frame, as is shown in the front edge of the check-hook bearing, Fig. 3, and springing the cut-out edges F F of the wooden mountings under the projections. By these means the wooden mountings are fitted with facility and exactness to the metal frame, and held securely,

with very little labor or expense. The cantel D is reduced in size in this improvement so that it begins only at its bearing-point or place of attachment, instead of extending, as heretofore, over the width of the saddle. By this means I make a saving in materials and add to the good appearance of the saddle. The cantel is strengthened at its base by a curved band-plate, d, to which the wood of the cantel is secured; and the band-plate is tapped to receive a screw, e, which goes up into it through the bearing C from beneath. The ends of the band-plate d extend on each side beyond the cantel and over the saddle-frame, to which its ends are secured by the additional fastenings f. When the jockey is omitted the band-plate d and the exposed part of the bearings C can be plated. That part of the metal frame A which is sunken to form the back-band channel is provided at its end, on its under side, with a rabbet and shoulder, G, which receives the end of a sheet-metal or other elastic prolongation, which is securely fastened to the rabbet of the frame. This prolongation H is perforated to allow the flap I to be fastened down smoothly to it. The square end of the frame A, on its upper surface, is met by the end of the middle part of the flap I, which is fastened to the elastic plate H, which part of the flap is slitted from the outer parts of the flap, (see Fig. 1,) and is bent down to the plate H, so as to form a continuation of the back-band channel. The bearings of the terrets J consist of removable plates K, arranged to slide over the back-band channel by a tongue and groove, or a dovetailed joint, or their equivalents, into connection with the sides of the back-band channel of the metal frame A, the sides of said channel being made higher at the places of connection, if desired, to obtain facility of access to the joint, as is shown in Fig. 1, where those parts are a little elevated for that purpose. The shanks L of the terrets are tapped to form nuts, which receive screws M that rise from the bearing-plates K, being

either fixed thereto, as shown in Fig. 5, or passing up through the plate, as is shown in Fig. 4. This mode of securing the terrets to the saddle is more simple and efficient than the old mode, by which the screw was made a permanent part of the terret, and was screwed down into the saddle-frame. The tapped terret is more easily made, is less liable to become broken, and can be more snugly fitted than by the old mode; the jockey N forming a sufficient washer for the connection, and forming, also, a fastening whereby, in combination with the terret and the screw M, the bearing-plate is securely held in place without being liable to slip out of its joint.

I have shown two methods of connecting the bearing-plates for the terrets to the saddle-frame. One of these consists (see Fig. 4,) in sliding the plate into the joint lengthwise of the saddle-frame, and the other in sliding it in cross-wise. Both of these methods are also shown in Fig. 1.

What I claim as new, and desire to secure by Letters Patent, is—

1. The combination of the elevated bearings C with the wooden mountings B, arranged, as described, so that the said mountings are recessed and fitted around said bearings, and also secured under their projecting edges, substantially as described.

2. The elastic prolongation H, arranged and combined, by a rabbet, with the under surface of the ends of the saddle-frame in continuation of the back-band channel, substantially as described.

3. The removable bearing-plates K, arranged over the back-band channel and connected with the saddle-frame by sliding connections, substantially as described.

This specification signed by me this 27th day of January, 1872.

VALENTINE BORST.
